UNITED STATES PATENT OFFICE.

CATHERINE SHIELS, OF NEW YORK, N. Y.

DESIGN FOR A MISS'S COSTUME.

SPECIFICATION forming part of Design No. 15,594, dated December 2, 1884.

Application filed October 1, 1884. Term of patent 3½ years.

To all whom it may concern:

Be it known that I, CATHERINE SHIELS, of the city, county, and State of New York, have invented and produced a new and original 5 Design for a Pattern of a Miss's Costume, (numbered 9,467;) and I do hereby declare that the engraved prints accompanying this specification convey to any one accustomed to using paper patterns a clear understanding of how 10 a garment made up by the pattern will appear.

The design shows a walking-skirt and an overdress. The skirt exhibits upon its front and sides a triple box-plaited drapery falling 15 even with its lower edge. The overdress displays a short pointed vest exhibiting a fastening all the way down, close-fitting polonaise-fronts flaring from the shoulders to a deep

point at each side, and exhibiting forward-turning plaits near their front edges from the 20 neck to the waist-line, and draping plaits in their back edges, a closely-fitted polonaise-back that exhibits a high draping upon the outside at the lower end of the center body-seam, plaits high up in its front edges, and 25 loopings at the center, coat-sleeves, and a standing collar.

What I claim as my invention, and desire to secure by Letters Patent, is—

The design for a miss's costume, as shown 30 in the engraved prints accompanying this specification.

CATHERINE SHIELS.
